UNITED STATES PATENT OFFICE

2,303,301

WINDOW SCREEN

Leland T. Milnor, Indian Hill, Ohio, assignor to
 The Cincinnati Fly Screen Company, Cincinnati,
 Ohio, a corporation of Ohio

Application February 9, 1942, Serial No. 430,061

4 Claims. (Cl. 160—328)

This invention relates to improvements in window screens of the type commercially referred to as frameless, having the screen fabric clipped within or bound at relative opposite ends respectively by a binding rail for direct attachment to the window frame, and upon tautly spanning the screen fabric, its longitudinal margins are brought into intimate contact with relative rails or strips designated as blind stops protruding from and a part of the window frame.

The screen with its bind strips or rails as a unit is readily attached and detached from the window frame, and can be compactly folded or rolled up for shipping and storage. The screen fabric generally is of a length and width of a size to shield the full area of window opening, and the binding rail at one end of the fabric is equipped for detachable mounting to the top of the window frame, and the second rail at the opposite or lower end for detachably connecting with the window sill and for drawing the fabric taut.

The present improvement is directed to simplify and increase the durability of the binding rails and their mode of attachment to the window frame to effect a reduction in cost over the prevailing types of binding rails employed for frameless screens, and to utilize a conventional sheet metal strip material commonly referred to as molding employed in the manufacture of metal frames for screens. The same strip material is employed for the binding rails at the opposite or top and bottom ends of the screen fabric, and provides for clinching the marginal end of the fabric within a channel in the rail by a channel form of beading or clamping strip compressed into the channel of the binding rail.

The beading or clamping strip is of improved form to adapt its use for clamping several different types of screen fabric, as for example, the conventional round wire square mesh screen fabric, and a second type designated as a shade screen fabric consisting of closely spaced, substantially parallel, thin gauge, flat metal strips as horizontals tied together in their spaced relation by strands of twisted wire as verticals, disposed a major spacing apart.

It is, therefore, an object of the invention to provide a frameless type of screen for window and other openings with rigid transverse sheet metal rails of duplicate structure for binding the relative or opposite top and bottom ends of the screen fabric for direct application to a window frame or opening framing, the rails cut from stock length or trimmed at one end to a length

size for a given or specific length of opening, and for edge or end binding various different styles or types of screen fabric, and to which conventional types of fasteners can be readily applied for quick attachment and detachment of the screen to the opening frame, and for drawing the screen fabric tautly in place.

Another object is to provide an improved screen of the frameless type of simple construction and low manufacturing cost, and adapting the parts to be easily and readily fitted and assembled to meet specific measurements at the place of installation as well as its application to the opening framing.

Various other features and advantages of the invention will be more fully set forth in a description of the accompanying drawing, in which:

Figure 1 is an elevation of a window frame fitted with a frameless window screen constructed in accordance with and illustrating an embodiment of the invention, the view being from the inner or operating side.

Figure 2 is an enlarged section on line 2—2, Figure 1.

Figure 3 is a section on line 3—3, Figure 2.

Figure 4 is a perspective view of a section of the beading or clamping strip for securing the screen fabric to a binding rail.

Figure 5 is an enlarged plan view of a portion of the screen, illustrating the improved beading or clamping strip for securing a shade screen fabric to the binding rails.

Figure 6 is a view similar to Figure 5, with the beading or clamping strip in a reverse position for securing the conventional square mesh wire screen fabric to a pair of binding rails.

In a frameless screen, a specific length and width of metal screen fabric appropriate for the size of window opening is provided at its top and bottom ends with transverse rigid rails to which the edge of the fabric is bound. The upper rail is detachably fastened to the upper cross rail of the window frame, preferably by means of devices operable from the inside, and the lower rail, heretofore generally consisting of a duplex or laterally extensible form of rail, is detachably fastened to the window sill. The longitudinal free edges or margins of the fabric overlappingly contact with the usual strip or blind stop projecting from the window frame.

Under the prevailing practice, the lower rail is composed of a plurality of strips relatively slidably joined for vertical or lateral extensibility of the rail, one strip connecting with the screen fabric, and the second locked to the sill. Means op-

erable from the inside are mounted on the bottom rail for forcibly moving the strips of the rail relatively to draw the screen fabric under tension and bring its longitudinal free margins in intimate contact with the window frame.

Considerable mechanical work is required for a proper fitting installation of the frameless screen to a window frame, and embodying a costly rail construction, and therefore, did not lend itself competitively with the frame type of screen, although the frameless type offers considerable advantage over the frame type in that it can be compactly rolled up and taken down for storage. The present improvement offers a reduction in manufacturing cost, greater convenience in making a window opening fitting as well as increasing its utility in its adaptability for use in connection with various styles and types of screen fabric.

Referring to the drawing, 1 indicates a conventional window frame composed of a pair of jambs 2, 2, top rail 3 connecting the upper ends of the jambs, and a sill 4 connecting the bottom ends of the jambs, each jamb and the cross rail having the usual blind stop or strip 5 projecting inwardly of the frame. The frameless screen comprises a top rail 6, a bottom rail 7, and a screen fabric 8 having its opposite ends respectively fixed to said top and bottom rails. The top and bottom rails 6 and 7 in the present instance are of duplicate construction and constitute definite lengths of sheet metal strip material in construction comparative to the conventional strip material employed in the manufacture of metal frames, and for example, of a cross-sectional formation, as shown and described in Letters Patent of the United States No. 1,743,935 to A. C. Schneider et al., January 14, 1930.

As illustrated, the strip is formed of a single sheet of metal shaped to comprise a rectangular hollow or tubular body portion 9 with the opposite longitudinal edge of the sheet metal brought together in a laminated extension at one end of the body portion and in plane with one side thereof to provide a base wall 10 of a channel 11 longitudinally at one end of the strip and formed by bending the free ends of the metal at a right angle to the base wall 9 to provide a laminated side wall 12 for the channel. The free end of the outer layer of the wall 12 is extended beyond the inner layer, and its edge marginally crimped inwardly upon itself for reinforcement and rounding the free edge of the channel wall.

The beading strip 13, for frictionally clamping the screen fabric into the channel, constitutes a strip of sheet metal bent into channel or U-form in cross-section with its free ends longitudinally of the strip marginally bent upon itself inwardly to reinforce and round the edge. One limb or flange of the beading strip is laterally notched or serrated. The notches 13a are disposed at definite uniform spacing apart and terminate slightly inward into the base wall or web and in a curved or rounded form. The notches provide a clearance for the vertical twisted wire strands 14 of a shade style metal screen fabric. The twisted wire strands loop about thin gauge flat wire horizontals 15 minutely spaced apart and have their flat sides parallel and set at a slight angle to the plane of the shade. This type of screen fabric for a frameless screen is advantageous over the square mesh woven type of screen fabric in that the horizontals can be cut between a pair of verticals to reduce the width of the fabric to meet a definite width of window

opening without danger of any unravel, and therefore, does not require the numerous various stock widths of screen fabric to meet a large range of different window opening widths as is necessitated with the woven square mesh type of screen fabric, which requires a selvage edge to prevent unravel.

Owing to the large degree of spacing of the verticals, a comparatively limited number of verticals are employed, and it is desirable to avoid impingement thereof which causes their breakage in binding the screen fabric within the rail. Impingement of the verticals is prevented in having the same extend in the notches of the beading strip. As the result desired is accomplished by notching only one flange of the beading strip, the second or opposite flange is left intact so that the strip can be reversed when utilized for binding the conventional square mesh wire screen fabric to a rail, as shown in Figure 6.

The top rail 6 at the inner side of the screen is provided with a plurality of fasteners or latches 16, each preferably in the form of a sheet metal stamping, consisting of a disc 17 rotatively bolted to the rail 6 by a bolt 18 traversing an aperture in the rail and held in place by a thumb nut 19 screw-threaded upon the bolt. The disc has a curved flange segment 20 extending laterally from one side thereof, and the flange is slotted for effecting a locking engagement with a screw 21 fixed into the window frame. A handle 22 integral with the disc extends radially therefrom. A slight arc of rotation of the disc moves the locking flange either into or out of engagement with the screw for attaching or detaching the rail to the window frame. The configuration of the notch in the locking flange and the curvature of the flange serves to draw the rail inwardly against the window frame, and also slightly outwardly. The rail is preferably provided with a series of lined apertures for adjustably positioning the latch fastener on the rail.

The lower rail 7 is equipped with a plurality of latches 23, the number being optional and depending upon the rail length; usually a pair will suffice. The latch is of conventional construction, comprising a base plate 24 fixed to the rail by a pair of screws and rotatively sustaining a disc 25 integrally having a handle extension and a cam or key element 26 at its rear side thereof traversing an aperture 27 in a hasp plate 28. Upon rotation of the key relative movement is imposed to the hasp plate. The hasp plate at its lower end has a laterally extended latch bar 29 adapted for interlocking connection with a latch plate 30 fixed to the window sill.

Upon interengaging the latch bar 29 with the latch plate, and rotating the key or cam by its actuating handle in an appropriated direction or arc of revolution, the rail 7 is depressed, locking the rail to the sill and drawing the screen fabric under tension to an ample degree of tautness and bringing its longitudinal free margins into intimate contact with the blind stops of the window frame.

Moving the latch handle in a reverse direction will move the latch plate downwardly or outwardly, releasing the tension on the screen fabric and permitting the lock bar to be unhooked or disengaged from the latch plate 30 and release of the lower rail, so that the screen fabric with its lower rail can be swung outwardly without release of the top rail for access to the window panes for cleansing.

Having described my invention, I claim:

1. In a frameless screen for a framed window or like opening having a screen fabric for screening the opening, rails for respectively rigidly binding relative opposite ends of the screen fabric, the rails formed of sheet metal and of duplicate cross section, each having a channel longitudinally in one side thereof for the reception of an end margin of the screen fabric and fastener devices respectively fixed to said binding rails for removably attaching the rails to the opening framing respectively at the top and bottom thereof and for drawing the screen fabric under tension; a beading strip of U-form in cross section interfitting said channel for binding the margin of the screen fabric within the channel, one longitudinal flange of said strip laterally serrated providing a plurality of adjacent tongue sections, each adapted to be engaged between a pair of vertical strands of said screen fabric, the serrations providing a strand clearance.

2. A rail for binding an end of a screen fabric for a frameless type of screen, the rail having a longitudinal channel in one side thereof for the reception of an edge of the screen fabric, and a strip U-form in cross section for interengag-

ment in said channel, one limb thereof having a series of lateral notches subdividing the limb into a plurality of tongues, each for engagement through the mesh of the screen fabric between adjacent pairs of longitudinal strands of the fabric, each notch providing a clearance for a vertical strand of the screen fabric in binding the fabric to the rail.

3. A rail for binding an end of a screen fabric, the rail having a longitudinal channel in one side thereof for the reception of an edge margin of the screen fabric, and a channel strip intermeshing in said channel for binding the fabric in the channel having one limb thereof laterally serrated, each serration providing a clearance for a vertical strand of the screen fabric in binding the fabric to the rail.

4. A binding strip for intermesh within a channel in a rail for securing an edge of a screen fabric to the rail, the strip being of channel form in cross section having one limb thereof laterally serrated, each serration providing a clearance for a vertical strand of the screen fabric in binding the fabric to the rail.
